Primary Examiner — Kelley Donnelly(74) Attorney, Agent, or Firm — Schwabe, Williamson & Wyatt P.C.(57) CLAIM

We claim the ornamental design for an upright merchandise display rack, as shown and described.

DESCRIPTION

FIG. 1 is a top front perspective view of a merchandise display rack according to an embodiment of the present invention;

FIG. 2 is a top back perspective view thereof;

FIG. 3 is a front elevational view thereof;

FIG. 4 is a back elevational view thereof;

FIG. 5 is a left elevational view thereof;

FIG. 6 is a right elevational view thereof, and,

FIG. 7 is a top plan view thereof.

The broken lines are for illustrative purposes only and form no part of the claimed design.
